UNITED STATES PATENT OFFICE

2,369,623

HAT STEAMER

Ray C. Utley and Arthur Feilchenfeld, Jr.,
Chicago, Ill.

Application March 1, 1943, Serial No. 477,544

11 Claims. (Cl. 219—38)

In our prior Patent No. 2,276,809, we have disclosed a small, portable apparatus for rapidly generating steam and discharging it in a manner to permit successful steaming of hats or other articles. The object of the present invention is further to improve the apparatus disclosed in the aforesaid patent.

When steam is generated rapidly and allowed to escape it is apt to carry with it water in liquid form. In our prior patent, in order to permit the liquid water to become separated from the steam and collect on surfaces down which it may travel to reach the body of water that is being heated, we make the delivery pipes quite long. One of the objects of the present invention is to do away with the need for long delivery pipes, thereby conserving material and space, making possible a more compact structure and simplifying the problem of maintaining the exterior of the apparatus at an unobjectionably low temperature.

A further object of the present invention is to provide a simple and novel means for collecting sediment that may be deposited in the apparatus, whereby the sediment will not interfere with either the proper supplying of water or efficient heating of the water to transform it into steam.

A further object of the present invention is to provide the steam generating apparatus with a simple and novel casing or housing which may easily be applied or removed, and which will not become objectionably hot during the use of the apparatus.

A further object of the present invention is to reduce the possibility of short circuits being created by the wires which carry the current to the heating coils.

The various features of novelty whereby our invention is characterized will hereinafter be pointed out with particularity in the claims; but, for a full understanding of our invention and of its objects and advantages, reference may be had to the following detailed description taken in connection with the accompanying drawings, wherein:

Figure 1 is a central vertical section through an apparatus embodying the present invention; Fig. 2 is a section on line 2—2 of Fig. 1; Fig. 3 is a section on line 3—3 of Fig. 1; Fig. 4 is a bottom plan view, a portion of the bottom wall being broken away; Fig. 5 is an end view, looking from the right hand side of Fig. 1; and Fig. 6 is a section on line 6—6 of Fig. 1.

The apparatus as a whole is, generally speaking, like that of our aforesaid patent, No. 2,276,-

809, and need only briefly be described. It comprises a suitable flat base 1, from which rises an open-top reservoir 2 upon which a bottle A is to be placed upside down. Rising from the base in spaced relation to each other and at one side of the reservoir, are two short sleeve-like projections 3. The parts 1, 2 and 3 may conveniently constitute a single casting, as shown. On the underside of the base is a tunnel or passage 4, one end of which communicates with the bottom of the reservoir, through an opening or port 5, while toward the other end are two ports 6 connecting the passage with the interiors of the sleeve-like parts 3. Screwed into the projections 3 are vertical pipes 7, which are quite short compared with the corresponding pipes in said patent. The upper ends of the pipes are connected together by an overlying hollow head 8, terminating in a nozzle 9. The interior of the head contains a transverse partition 10, separating it into a lower compartment communicating directly with the pipes 7, and an upper compartment which merges into the nozzle. This partition contains a central opening 11 which lies above the space between the two pipes, namely outwardly from the imaginary surfaces corresponding to the cylindrical surfaces of the inlets into the bottom of the head. The partition is inclined upwardly and laterally from opposite sides of the opening 11 so as to form directly above each of the pipes a pocket or dome located above the plane of the opening 11. Surrounding each of the pipes 7 is a heating coil 12; this part of the apparatus being preferably the same as that in the aforesaid patent.

When a full bottle of water is up-ended and set upon the reservoir, water will flow therefrom until it reaches a predetermined level in the reservoir and in the pipes 7. As water is transformed into steam, additional water is delivered from the bottle to maintain a constant level. As the steam is generated, it rises through the pipes and enters the pockets or domes in the head. Any liquid thus carried along with the steam therefore strikes the walls of the pockets or domes, collects thereon, and finally drops back into the bottom of the head. From there the water can flow back into the pipes. In this way, substantially all of the free water is separated from the steam before it begins to flow laterally so as to escape through the outlet 11, so that the steam discharged from the nozzle is in a condition that is satisfactory for the intended use to which it is to be put.

Sometimes sediment or other solid matter may collect in the bottom of the pipes, so that there is danger of clogging the ports 6. We have therefore provided each of the pipes with a settling well or basin in which a large amount of solid matter may collect without interfering in any way with the entrance of water into the pipes. In the arrangement shown, there is in the lower end of each pipe a member 14, in the form of a deep inverted cup, whose external diameter is considerably less than the internal pipe diameter. The open end of each cup terminates in a reduced portion or neck 15 that fits snugly into an enlarged upward continuation of the corresponding port 6. Each member 14 has one or more holes 17, extending through the cylindrical wall thereof, near the upper or closed end. Thus water rising through the port 6 must reach the level of the holes 17 before it enters the free space within the pipes; and since this level is considerably above the bottom of such space, an annular pocket or well is provided below the immediate water inlet to each pipe. Each member 14 may be connected to the lower end of a rod 19, carrying the little wire mesh disks 18 as in the aforesaid patent.

We have found that when our steamers are carelessly handled, as they frequently are, there is danger of damage to the insulation of the wires 21 that bring the current to the terminals 22 of the heating coils. Therefore, as best shown in Figs. 4 and 6, we carry these wires through long tubes 24 of insulating material which extend between and through vanes or ears 25 and 26 projecting downwardly from the inside of the base; the vanes or ears 25 being close to the terminals 22 whereas the others are near the end of the base at which the electrical connections are made.

The base has at the four corners thereof downwardly projecting lugs 27. Underlying and engaged with these lugs is a false bottom composed preferably of a metal plate 28 and a sheet 29 of insulating material overlying the plate. The plate may be secured to the lugs 27 by attaching means including feet 30 on which the structure is supported.

The entire device or apparatus is enclosed within a housing or casing, not only for the sake of improving the appearance thereof but to protect the same and to insure that all exposed surfaces, excepting only the extreme end of the nozzle, remain cool even through prolonged periods of use. The casing or housing is without a bottom but covers the device on top and on all sides, leaving openings only for the tip of the nozzle and the top of the reservoir. The casing or housing is conveniently formed of two similar sections 31 and 32 meeting in the longitudinal vertical central plane of the steamer. The two sections are preferably provided at their meeting edges with means that interlock, when the two sections are brought together by lateral movements, to prevent relative movements in other directions. This may conveniently be accomplished as in Fig. 2 in which the section 31 has at its vertical edges a pair of bosses 34 which engage with similar bosses 35 on the other section. Each of the bosses 35 is provided with a pin 36 fixed thereto and adapted to be engaged in a hole 33 in the corresponding boss 34 when the two sections are brought together. The two sections may be fastened together by a single screw passing through one of the sections and into the other at a point between the reservoir and the pipes 7.

It is desirable that the casing or housing be spaced apart from the metal parts that may be-

come heated, so as to provide an insulating air space between the latter and the casing. This makes it necessary to cause the housing to be held in a fixed relation to the apparatus proper by some means that would not be required if the casing were a tight fit. In the arrangement shown, the base is provided at its long sides near the four corners with thin flange-like sections 38, unless the base itself be of the necessary thinness. These portions enter notches 39 in ears 40 projecting inwardly from the side walls of the casing. The parts are so proportioned that, when the two sections of the casing are assembled on the device, the flanges 38 enter the notches 39 and are clamped in the same upon the tightening of the screw 37. The casing is therefore readily attached to the apparatus and is supported thereby, through being clamped against the same at four points. In order that the casing be not required to support the weight of the steaming apparatus, the feet 30 are permitted to extend a substantial distance below the plane of the lower edge of the casing as best shown in Fig. 1, so that the weight of the whole structure, including the casing, is borne by these feet.

While we have illustrated and described with particularity only a single preferred form of our invention, we do not desire to be limited to the exact structural details thus illustrated and described; but intend to cover all forms and arrangements which come within the definitions of our invention constituting the appended claims.

We claim:

1. In an apparatus of the character described, a vertical pipe through which steam rises during use, there being above and carried by the pipe a hollow head wider than the diameter of the pipe and divided into an upper and a lower compartment by a transverse partition, the portion of the head containing the upper compartment terminating in a nozzle, there being an opening through said partition at a substantial distance beyond one side of an imaginary upward extension of the periphery of the pipe, and said partition being shaped to form a dome directly above said pipe to trap all of the steam that rises from the pipe before it can flow through said opening.

2. In an apparatus of the character described, a pair of vertical pipes spaced apart from each other, through which steam rises in use; a hollow head overlying and attached to the upper ends of the pipes; the interior of the head being divided into an upper and a lower compartment by a transverse partition, the upper compartment terminating in a nozzle; and said partition having therein, at a point between the pipes, an outlet from the lower compartment into the upper compartment.

3. In an apparatus of the character described, a pair of vertical pipes spaced apart from each other, through which steam rises in use; a hollow head overlying and attached to the upper ends of the pipes; the interior of the head being divided into an upper and a lower compartment by a transverse partition, the upper compartment terminating in a nozzle; said partition having therein, at a point between the pipes, an outlet from the lower compartment into the upper compartment; and said partition having upward bulges above said pipes to form pockets into which the steam must rise before flowing laterally to said outlet.

4. In an apparatus of the character described, a base; a pipe rising from said base and having an outlet at the upper end, an inverted cup-shaped

member smaller in diameter than the interior of the pipe located in the pipe in engagement with the base, said cup-shaped member having an outlet for water toward the top, and there being a hole through the base into the bottom of said member, whereby any solids deposited in the pipe may settle into the space around said cup-shaped member below said outlet and be rendered harmless to choke the water inlet to the pipe.

5. In an apparatus of the character described, a base, a pipe rising from the base, the base having a hole coaxial with the pipe, and an inverted cup-shaped member, smaller in diameter than the pipe fitting tightly into said hole, said member having an opening through a wall thereof at a substantial distance above the base to provide a settling well in the lower end of the pipe below said opening in the cup-shaped member.

6. In an apparatus of the character described, a base, a pipe rising from the base and open at its upper end, the base having therein coaxial with the pipe a hole for the passage of water into the pipe, an inverted cup-shaped member fitting into said hole and having holes through the wall thereof near the top, and a stem fixed to said cup-shaped member and extending up through the center of the pipe.

7. In an apparatus of the character described, a base, a pipe rising from the base and open at its upper end, the base having therein coaxial with the pipe a hole for the passage of water into the pipe, an inverted cup-shaped member fitting into said hole and having holes through the wall thereof near the top, a stem fixed to said cup-shaped member and extending up through the center of the pipe, and a plurality of open-work disks distributed along the stem and forming a series of transverse partitions in the pipe.

8. In an apparatus of the character described in which there is a base member and electric heating means for water mounted on top of the base, an electric terminal on the under side of

the base, an ear projecting down from the base near said terminal, a second ear remote from the other ear, a tube of insulating material extending through and supported by said ears, and a conductor enclosed by said tube and connected to said terminal.

9. In an apparatus of the character described, in which there is a base member and electric heating means for water mounted on top of the base, an electric terminal on the under side of the base, an ear projecting down from the base near said terminal, a second ear remote from the other ear, a tube of insulating material extending through and supported by said ears, a conductor enclosed by said tube and connected to said terminal, and a rigid plate underlying and fixed to the base and forming a cover for the said tube and terminal.

10. In an apparatus of the character described, a main body member having supporting feet and thin horizontal side flanges projecting therefrom near the lower end, a casing surrounding said member and divided on a vertical plane into two sections each of which can be moved laterally into and out of position, each section containing channels to receive the flanges on the corresponding side of said member, and means to secure said sections together.

11. In an apparatus of the character described, a main body member having supporting feet and thin horizontal side flanges projecting therefrom near the lower end, a casing surrounding said member and divided on a vertical plane into two sections each of which can be moved laterally into and out of position, each section containing channels to receive the flanges on the corresponding side of said member, and a single screw extending between and securing said sections together.
